COMBINED FACE, DISC AND HAND FOR A 24 HOUR TIMEPIECE

Lewis W. Morris, 2826 Fairhaven Ave., Alexandria, Va.

Filed July 22, 1965, Ser. No. 86,259

Term of patent 14 years

(Cl. D42—1)

FIG. 1.

FIG. 2.

FIGURE 1 is a top plan view of a combined face, disc and hand for a watch showing my new design. The broken lines showing of a portion of a wrist watch is for illustrative purposes only.

FIGURE 2 is an end view of said combined face, disc and hand for a watch.

The broken-line showing of a watchcase in FIG. 1 is for illustrative purposes only.

I claim:

The ornamental design for a combined face, disc and hand for a 24 hour timepiece, as shown and described.
